United States Patent Office.

DAVID E. HALL, OF DETROIT, MICHIGAN.

Letters Patent No. 79,116, dated June 23, 1868.

IMPROVEMENT IN JOINT-CLAMPS.

The Schedule referred to in these Letters Patent and making part of the same.

TO ALL WHOM IT MAY CONCERN:

Be it known that I, DAVID E. HALL, of Detroit, in the county of Wayne, and State of Michigan, have invented certain new and useful Improvements in Joint-Clamps; and I do hereby declare that the following is a full and complete description of the same, reference being had to the accompanying drawings, making part of this specification, in which—

Figure 1 is a side view of the clamp.

Figure 2, a view of the edge.

Figure 3, a perspective view of a corner of a box, with the clamp in place.

Like letters of reference refer to like parts in the different views.

This clamp consists of a thin plate of steel or other metal, fig. 1, bent at a right angle through its diameter, as shown in fig. 2. On each wing of the clamp, and on both sides of the same, are struck up barbs, A, the points of which, as will be seen, are in the direction of the angle, the purpose of which will hereafter be shown.

The practical use of this clamp is for staying the corner-joints of boxes, picture-frames, &c., thereby dispensing with the use of nails, or the insertion of ties, as is usually done for this purpose, the clamp being much stronger, and wholly unseen when applied, which is done as follows, viz.:

In fig. 3, B represents the sides of a box, the joint of which is a mitre. In the edge of the joint is sawn a groove, of the thickness of that of the clamp. Into these grooves are inserted the wings of the clamp, and which are forced in on bringing the joint together, thereby bringing the clamp in the wood, as indicated by the dotted lines C, fig. 3, the sharp-pointed barbs preventing the clamp from pulling out, so that the joint is held strongly together, requiring no nails, glue, or any other fastening for ordinary work.

I do not confine myself to any particular shape of the clamp. A narrow plate, bent to the proper angle, and provided with barbs, may be used with good results, in securing the joint, by inserting it in the same manner.

What I claim as my improvement, and desire to secure by Letters Patent, is—

The herein-described metallic clamp, when constructed in the manner as and for the purpose set forth.
